United States Patent Office

Des. 198,806
Patented Aug. 4, 1964

198,806

PERCOLATOR OR THE LIKE

Frank J. Chiappetta, Elmira, and George W. Richardson,
Corning, N.Y., assignors to Corning Glass Works,
Corning, N.Y., a corporation of New York

Filed Mar. 24, 1964, Ser. No. 79,144

Term of patent 14 years

(Cl. D44—26)

Fig. 2

Fig. 1

FIGURE 1 is a front elevational view of a percolator embodying our new design.

FIGURE 2 is a side elevational view of the percolator shown in FIGURE 1.

FIGURE 3 is a rear elevational view of the percolator shown in FIGURE 1.

FIGURE 4 is a top plan view of the percolator shown in FIGURE 1.

FIGURE 5 is a bottom plan view of the percolator shown in FIGURE 1.

We claim:

The ornamental design for a percolator or the like, as shown.
